7 Claims. (Cl. 28—4)

10

This invention relates to a needle. More particularly it relates to a novel needle particularly useful in the felting and fulling arts.

In accordance with the present invention a novel needle which has an irregular profile is provided. It will be referred to hereinafter as a "rasping-profile needle." By a "rasping-profile" is meant that an elevational view of the needle discloses at least one abrupt, hookless break, i. e., a notch or a protuberance having a substantially smooth surface, in the continuity of its edge. By "abrupt" is meant that the extent of the profile discontinuity along the longitudinal axis of the needle is no more than about five or six times the extent of its discontinuity normal to the said longitudinal axis. By a "hookless break" is meant a discontinuity of such shape that as the tangent to the discontinuity is progressed in either direction from the point wherein it is parallel to the longitudinal axis of the needle, it will never change more than about 90° in any one direction without disrupting tangential contact. The term tangent includes a line or plane contacting a position on a straight line portion of the discontinuity as well as the common meaning of tangent which includes a straight line or plane in contact with a point or curved surface or a curved line or plane in contact with a straight surface. By the term "progressed" is meant that as the line or plane follows the contour of the discontinuity to positions tangential to the discontinuity, whether tangential to straight lines or curved surfaces, it will sweep out an arc of no more than about 90 degrees. This needle is useful in the fulling process described in U. S. application, Serial No. 415,196, filed March 10, 1954, in the name of George Leslie Moler. It is also useful in a process for forming a coherent, non-woven, felt-like product by needling a loose batt of a fibrous mass containing a substantial proportion of retractable synthetic filaments, thereby forcibly orienting some of the retractable filaments into a position substantially perpendicular to the ultimate faces of the product and thereafter retracting the filaments by appropriate treatment with heat, swelling agent or the like as described in U. S. application No. 312,067, filed September 29, 1952, in the name of Herbert G. Lauterbach, and now abandoned.

It is an object of the present invention to provide a novel needle useful in the textile arts.

Another object is to provide a rasping-profile needle, and a process for making such a needle.

Another object is to provide a needle useful in the fulling of natural and synthetic woven and knitted fabrics.

Another object is to provide a needle useful in the felting of retractable synthetic filaments.

These and other objects will become apparent in the course of the following specification and claims.

The details of the present invention will be more readily understood by reference to the following drawings and description.

Figure 1 is an illustration of a commercially available barbed needle;

2

Figure 1a is a fragmentary view of the blade of the needle of Figure 1 exemplifying various dimensions;

Figure 2 is an illustration of a rasping-profile needle of the present invention prepared from the needle of Figure 1;

Figure 2a is a fragmentary view of the blade of the needle of Figure 2 exemplifying various dimensions;

Figure 3 shows a needle containing barbs in a reverse direction to those upon the needle of Figure 1;

Figure 4 illustrates a rasping-profile needle prepared from the barbed needle of Figure 3.

Figures 5 to 16 inclusive are fragmentary elevations of a rasping-profile needle illustrating variations in the nature of the profile discontinuity within the definition of an abrupt, hookless break.

Figure 5 is a fragmentary elevation of a rasping-profile needle wherein the abrupt, hookless break is a sharp protuberance.

Figure 6 shows a needle profile containing a sharp notch.

Figure 7 illustrates a combination of a sharp notch and a sharp protuberance.

Figure 8 exemplifies a sharp protuberance and a rounded notch.

Figure 9 is a needle profile containing a rounded protuberance.

Figure 10 is a needle profile wherein the notch is rounded.

Figure 11 is a view of a needle profile with a combination of a rounded protuberance and a rounded notch.

Figure 12 shows a needle combining a rounded protuberance and a sharp notch.

Figure 13 is a view of a long sharp notch in a needle profile.

Figure 14 illustrates a long sharp protuberance in a needle profile.

Figure 15 exemplifies a needle having a long rounded notch.

Figure 16 is a view of a rasping-profile needle wherein a rounded protuberance containing a sharp notch provides profile discontinuity.

Referring particularly to Figure 1, this is an elevation of a barbed needle of the prior art. It will be apparent that as the tangent to the notch (i. e., the tangent at the apex of the notch angle) is progressed from a point where it is parallel to the longitudinal axis of the needle, around the discontinuity toward the anchoring end of the needle, it describes an angle of substantially more than 90°. Note also that progression of the tangent from the tip of the protuberance where it is parallel to the longitudinal axis toward the needle point causes an angle substantially greater than 90° to be described. This irregularity is in the form of a hook. Neither this needle nor that of Figure 3, therefore, is within the definition of a rasping-profile needle.

Figures 2 and 4 each illustrate a rasping-profile needle. The break in continuity is abrupt and hookless. Figures 5 to 16 inclusive illustrate various suitable profile continuity breaks within the definition of a rasping-profile.

The following examples are cited to illustrate the invention. They are not intended to limit it in any manner. The barbed needles of Examples 3 and 8 were obtained from the Textile Machine Works of Reading, Pennsylvania. The other barbed needles of Examples 1 to 10 inclusive were acquired from the Torrington Company of Torrington, Connecticut. Each of the barbed needles have triangular cross-sections along their blades. In the system of needle designation the figures represent the following dimensions:

Butt x middle section x blade x overall length. The unit of length is inches. All other dimensions are in terms of wire gauge. The blade gauge is determined by

fore triangulation. The effective cross-sectional dimension (indicated as "D") reported for comparison purposes, is the measurement of the maximum thickness of blade cross-section in inches representing the average of several micrometer measurements at points of apparent maximum thickness including protuberances where present. The dimension A is the maximum variation in inches measured perpendicularly from the continuous profile due to a protuberance. The dimension B is the maximum variation in inches measured perpendicularly from the continuous profile due to a notch. The angle α is the angle subtended by the lines drawn from the upper and lower points of profile continuity to the deepest point within the notch. These dimensions are illustrated in Figures 1a and 2a. In each example, 1125 needles are suspended point down with only the blades submerged in 4400 cc. of C. P. reagent 37% hydrochloric acid (in water). This is about 4 cc. of acid per needle. A glass tray serves to hold the acid. Unless otherwise noted, fresh acid is substituted about every 2½ hours. In each case the solutions are at room temperature and unagitated. The blades are spaced sufficiently to avoid contact with one another. After etching the needles are rinsed with water to remove acid and thereafter dried.

Rasp-profile needles prepared as described above are particularly valuable in the production of a coherent, non-woven, felt-like product from a loose batt of a fibrous mass containing a substantial proportion of retractable synthetic filament as described in U. S. application No. 312,067. This process is illustrated in Examples 11 to 15 inclusive which follow. In each example about 1400 needles are mounted on the needle boards of a 36 inch James Hunter Machine Company needle-loom. The loom runs at 250 revolutions per minute. The feed advances while the needles are drawn clear of it at the rate of 0.285 inch per needle oscillation. The properties of the felts produced, namely, thickness in inches, tensile strength (longitudinal or transverse) in pounds per square inch and splitting resistance in pounds per two-inch width, are determined according to A. S. T. M. Designation D461-53 entitled "Standard Methods of Testing Felt."

Example 11

The needle loom is equipped with the etched needles of Example 1. A quantity of three denier, spontaneously crimpable polyethylene terephthalate filament is prepared by extruding through a spinneret and drawing in an air jet as disclosed in U. S. Patent 2,604,689 to Hebler. The filaments are cut into 2½ inch staple fibers and without relaxing are carded as in conventional textile operations. A batt thirty inches wide, is formed from the carded layers to a depth of about 3 inches and weighing 3.1 pounds per square yard. The batt is fed through the needle loom for a total of 20 passes, the batt being turned over after each pass. It receives about 2100 punchings per square inch. During this step the 75

batt area increases about 25%. The needle punched batt is immersed in boiling water for 2 minutes. It shrinks about 50% in area. The felt is dried. It has a final thickness of 0.370 inch and weighs 6.2 pounds per square yard. Its longitudinal tensile strength is 1,580 pounds per square inch while its splitting resistance is 59 pounds per two inch width. The product has a good appearance with but few visible needle marks. It is particularly useful in felt applications where unusual strength is required.

Example 12

The needle loom is equipped with the unetched needles of Example 1. The process of Example 11 is repeated. After the 20 passes the needled batt decreases in density to the point that a felt can no longer be produced. The best felt made with these needles is shrunk after two passes through the loom (one pass on each side). It is 0.5 inch thick, weighs 5.9 pounds per square yard, has a tensile strength of 630 pounds per square inch and a splitting resistance of 18 pounds per two inch width. In addition to its relatively poor strength characteristics, this felt contains visible needle marks and exhibits

tufts of fibers vertically oriented on the surface opposite to that in which the needles are last introduced.

Example 13

The needle loom is equipped with the etched needles of Example 10. A batt of carded layers about 5 inches deep, weighing 4.8 pounds per square yard is formed from seven denier per filament, three inch staple polyethylene terephthalate, prepared as described in Example 11. The batt is fed to the loom for a total of five passes, resulting in about 525 needle punchings per square inch. The needled batt is shrunk 40% in area by passing through a hot air oven at 200° C. for 5 minutes. The felt product weighs eight pounds per square yard. After pressing at 120° C. for two minutes under a pressure of five hundred pounds per square inch, it has an average thickness of 0.340 inch. The average splitting resistance is 21.3 pounds per two inch width. Longitudinal tensile strength is 940 pounds per square inch. The product is dense and contains but few visible needle marks. It is useful as a glass polishing felt.

Example 14

The needle loom as equipped in Example 13 is fed the batt of Example 13 for a total of 31 passes (about 3255 punchings per square inch). The needled batt is shrunk in boiling water as taught previously. It is not pressed. The resulting felt weighs 9.6 pounds per square yard and is 0.50 inch thick. It has a splitting resistance of 68 pounds per two inch width. The longitudinal tensile strength is in excess of 1000 pounds per square

inch. This thick felt of high density is useful as a polishing felt.

Example 15

The needle loom is equipped with the etched needles of Example 1. A batt of carded layers is formed containing about 75% 3 denier per filament 3 inch staple and about 25% 6 denier per filament 3 inch staple polyethylene terephthalate. The batt is about 1 inch deep and weighs about 3 ounces per square yard. It is passed through the loom 24 times (an average of about 2520 punchings per square inch). It is shrunk 58% by immersion in boiling water for 1 minute. A lightweight felt is formed weighing about 7 ounces per square yard. It has a transverse tensile strength of 600 pounds per square inch, a longitudinal tensile strength of 700 pounds per square inch and a thickness of 0.045 inch. It is suitable for use in skirts and other apparel due to its crease resistance, bending length and liveliness.

The use of the rasping-profile needle as described herein in the preparation of felt-like products in the manner illustrated above permits as much as a ten-fold increase in the number of penetrations per square inch which are possible without weakening the final product than is possible with the barbed needle of the prior art. The increase in penetrations results in a stronger, more uniform and better appearing product. This is believed due to the increased and more homogeneous entanglement of the vertically oriented fibers. Thus thinner products of acceptable quality may be formed using the rasping-profile needle than was previously possible. Furthermore, in the production of thick felts, less needle breakage is observed with the needle of the invention as compared with a barbed needle. Not only is there a reduction of needle mark size in the product when the rasping-profile needle is employed, but surface tufts, as was described in Example 12 are eliminated.

The etched needles of the present invention are also valuable in the fulling of woven and knitted fabrics by the process taught in U. S. application 415,196 filed March 10, 1954, in the name of George Leslie Moler. In that process woven and knitted fabric is fulled by subjecting it to "multiple needling," i. e., a recurrent piercing and withdrawing of a needle of special characteristic and including a rasping-profile needle until migration of fibers into adjacent or crossing yarns is attained. This use of the rasping-profile needle is exemplified below. The loom equipment is the same as that previously described in connection with the felting of non-woven fabrics.

Example 16

The needle-loom is equipped with the etched needles of Example 1. A Shetland tweed type of fabric with a 2 x 2 twill construction and having a weave count of 32 x 30 is woven from a yarn containing a stock blend of 20% wool and 80% 3 denier, 2½ inch length polyacrylonitrile staple. The fiber is spun into an 18/2 cotton count yarn. The singles have a **Z** twist of 11 turns per inch and are plied with an **S** twist of 10 turns per inch. A portion of the yarn is dyed brown before weaving, so that the woven fabric consists of a pattern of brown and white. A sample of this fabric 20 inches wide is fed through the needle loom 25 times. This produces a total of about 3,500 punchings per square inch of fabric surface. The punched fabric possesses more covering power, is softer and has more nap than the original sample. It is also bulkier, its thickness having increased from 0.026 inch to 0.032 inch. The intermigration of colored and white fibers produces a pleasant blending which tones down the sharp pattern contrasts.

Example 17

A woman's sweater is knitted on a 12-cut circular knitting machine from a yarn of polyacrylonitrile staple. The fiber is spun into a 2/24 worsted count yarn from 3

denier staple, 2½" long. The singles are twisted 10 turns **Z** to the inch. The ply contains 6½ turns **S** to the inch. The sweater is dyed yellow. It is then fed to the needle loom as equipped with the etched needles of Example 1 for a total of 28 passes. This is a total of about 3800 punchings per square inch. The covering power of the needle-punched sweater is increased so that whereas when ultra violet light is directed at the samples the original sweater transmits 6.3% of the light while the needled sweater transmits only 0.4% as recorded on a photo-electric cell. The needle-punched sweater is fulled despite the fact that the yarn from which it is knitted contains no wool. It has a softer hand, greater bulk and is less sleazy as compared with its condition before punching. When the loom is equipped with the unetched needles of Example 1, many yarns of fabric are rent without fulling after only a few passes of the fabric through the loom.

20 A rasping-profile needle is the preferred type of needle in the fulling process as exemplified in Examples 16 and 17 above. Where the profile discontinuity is not essentially hookless, i. e., where a tangent to the discontinuity, progressed in either direction from the point 25 wherein it is parallel to the longitudinal axis of the needle, sweeps out an angle of more than about 90°, the needle tends to rend the fabric yarns causing the fabric to be weakened and in some cases disintegrated.

Since fulling by "multiple needling" of woven and 30 knitted fabrics is not feasible with barbed needles, effects formerly unattainable are made possible by the rasping-profile needle structure. The effects attainable by use of the rasping-profile needle in fulling woven and knitted fabrics include removal of fabric wrinkles, uniformity, 35 surface levelness, improved hand, nap and an increase in fabric bulk, covering power, stiffness and body.

The cross-sectional shape of the blade of the needle of the present invention is not critical. The needles exemplified have a blade of triangular cross-section.

40 However, other shapes such as round, flat, elliptical, square, rectangular, hexagonal or the like, may be used. It is preferred, in any case, that the cross-sectional dimension of the blade **D** be maintained at as low a value as possible consonant with strength requirements. Usually 45 a blade having a cross-sectional dimension of about 0.050 inch is satisfactory. Fabrics of very fine, relatively delicate yarn, especially where the fabric has a tight weave may require a somewhat finer needle. For most household clothing and industrial fabrics a dimension **D** within the range of about 0.020 to about 0.040 inch is adequate. However, at times a dimension **D** as low as about 0.010 inch is advisable. Since the piercing end of the blade terminates in a point it is obvious that the blade will be tapered at its piercing end. If desired 50 the entire blade section may be so tapered.

55 The hookless-break which produces the profile discontinuity along the blade of the rasping needle is preferably of the notch variety. While the notch depth, dimension **B** as previously defined, may vary widely, depending upon the type of function to which it is to be applied and the properties of the fabric fed to the needle loom, a depth within the limits of about 0.002 to about 0.012 inch is generally employed. Usually it is maintained within the limits of about 0.002 and 0.008 inch. In 60 general the deeper notches are satisfactory with coarse weaves of higher denier, high twist, tough yarn. Tight weaves of low denier, delicate, low twist yarns make choice of a needle with a blade of shallower notches desirable. Where the profile discontinuity is created by a hookless protuberance, it is preferably no greater than 65 about 0.001 inch whether or not it is in combination with a notch.

The profile discontinuity of the needle blade is disposed substantially horizontally across the blade when the needle is held vertical. Where a notch produces

the discontinuity, it is preferred that its angle, i. e., α as defined previously, be at least 90° , although notches of smaller angles are sometimes operable. A range of notch angle, α , between about 110° and 160° has been found to produce optimum results in felting and fulling fabrics as described above under usual operating conditions. Needle properties, such as blade length, number and distribution of profile discontinuities, speed of operation, have not been observed to have any critical effect on finished fabric properties. The felting and fulling processes are affected by such needle variations only to the extent that the number of punchings to attain a desired result will vary.

The preferred process for the manufacture of a metal rasping-profile needle is by etching a needle having a barbed blade by suspending the needle so that its blade is immersed in an acid solution. The etching process tends to remove the "hook" of the barb while usually decreasing the cross-sectional dimension D, the maximum protuberance A, the notch depth B and the overall length of the blade. The notch angle α increases. Other general effects of the etching process include a sharpening of the needle point and a sharpening of any edges along the blade length. The usual etching bath is a 37% solution of hydrochloric acid in water. Other acids may be employed in place of the hydrochloric. In the etching procedure, spent acid is preferably replaced with fresh acid at intervals. The period necessary to transform a barbed needle to a rasping-profile needle will depend on many factors such as the etching bath composition, the material of needle construction, the dimensions of the blade of the unetched needle and the like. The period necessary can be approximated by comparing with the period required for a Torrington No. 25 regular barb steel needle etched with the 37% hydrochloric acid using about 4 cc. of acid per needle, replaced at intervals of about $2\frac{1}{2}$ hours. This needle, commonly designated as 15 x 18 x 25 x $3\frac{1}{2}$ regular barb is manufactured by the Torrington Company of Torrington, Connecticut. Its overall length is $3\frac{1}{2}$ inches. It has a round sharp point which tapers to an equilateral triangular cross-sectional dimension of 0.039 inch. It contains 9 barbs staggered evenly along the blade about 0.25 inch apart, 3 barbs on an edge. The first and last barbs are 0.25 and 1 inch respectively from the point. The blade (i. e., the working section including the point) is about 1.1 inches in length. The removal of the protruding hook to bring it within the definition of a rasping-profile needle requires a minimum of about 4 hours etching at room temperature. In general, such needles etched for a period of from about 4 to about 16 hours give satisfactory results. Such treatment reduces the cross-sectional dimension D about 30 to 40%. The protruding discontinuity (dimension A) disappears at about 4 hours. The preferred needles are those treated from 6 to 10 hours. Under these conditions the notch angle α increases to within about 110° to about 160° . The notch depth B is within the range of about 0.002 to 0.008 inch. The length of the blade decreases about 3% after etching for 7 hours as described above. The optimum etching period for any particular needle can be approximated by a comparison with the above. More exact figures can be obtained empirically.

The etching process may be modified by the use of agitation, heat, abrasion or the like. For instance, the process may be speeded up by making a thick slurry of abrasive material in acid and rotating the barbed needle in the slurry. A straight edge needle may be given a coating of an acid resistant material which coating is perforated where notches are desired. Rasping-profile needles may be prepared by methods other than etching. The profile discontinuities may be introduced by spot welding,

grinding, polishing, firing, sand blasting, swaging, liquid honing, or other mechanical means. The notches may be introduced by striking the needle normal to its longitudinal axis with a sharp instrument, by filing and the like.

5 While metal, specifically steel, is the preferred material of construction, other substances such as glass, ceramic, plastic or the like may likewise be employed. A plastic needle makes production of rasping-profile needles possible by extrusion or injection molding, an extremely fast and inexpensive method.

While the rasping-profile needle of this invention is particularly useful in the forming of coherent felt-like products containing a substantial proportion of retractable synthetic filaments and in the fulling of fabrics by multiple needling, it will be obvious that many other uses are possible. Thus it may be employed for loosely locking an unwoven batt with or without shrinkage. It may be used to edge a batt, a woven or knitted fabric or to create novel designs in such materials. It is useful also in the 15 making of endless belts by joining, i. e., an interweaving of two ends of the same fabric followed by fulling to strengthen the join, in the manufacture of papermaker's felt and the like.

Typical examples of materials in the production of 20 which rasping-profile needles are valuable include natural or synthetic (or mixtures thereof) woven and non-woven products such as filter fabrics for both gas and liquid filtrations, papermaker's felts, polishing felts and fabrics, insulation, sound absorbents, blankets, wicking felts, 25 shock mounting felts, conveyor beltings, roll coverings, Sanforizing blankets, the fibrous component of plastic laminates and the like. Examples of household products are apparel, such as sweaters, suitings, hosiery, overcoatings, 30 underwear, shirting and blouse fabrics, headwear, carpets and their underliners, upholstery fabrics, draperies, boot linings and the like.

Many other modifications within the scope of the 35 above invention will be apparent to those skilled in the art without a departure from the inventive concept.

40 What is claimed is:

1. A needle whose profile continuity is broken along its body by at least one hookless break, said break being a discontinuity of such shape that as the tangent to the 45 discontinuity in the plane of the profile is progressed in either direction from the position where it is parallel to the longitudinal axis of the needle, it will sweep out an arc of no more than about 90° without disrupting tangential contact.
2. The needle of claim 1 wherein the discontinuity is a protuberance.
3. The needle of claim 1 wherein the discontinuity comprises a curved notch and a protuberance.
4. The needle of claim 1 wherein the discontinuity is a notch.
5. The needle of claim 4 wherein the notch angle alpha, as exemplified by Figure 2a, is at least 90° .
6. The needle of claim 4 wherein the profile of the notch is a smooth curve.
7. A needle having an irregular profile, the discontinuity being an abrupt, hookless break in the form of a notch, where the notch angle alpha, as exemplified by Figure 2a, is greater than 90° .
